UNITED STATES PATENT OFFICE

168,431

WINDOW DECORATIVE PANEL OR SIMILAR ARTICLE

Bernard Yellin, Chicago, Ill., assignor to Bernard
Edward Co., Chicago, Ill., a corporation of Illinois

Application August 25, 1952, Serial No. 21,175

Term of patent 14 years

(Cl. D21—6)

To all whom it may concern:

Be it known that I, Bernard Yellin, a citizen of the United States and a resident of the city of Chicago, county of Cook, State of Illinois, have invented a new, original, and ornamental Design for a Window Decorative Panel or Similar Article, of which the following is a specification, reference being had to the accompanying drawing, forming a part thereof, in which:

Figure 1 is a plan view of a window decorative panel or similar article showing my new design; and

I claim:

The ornamental design for a window decorative panel or similar article, substantially as shown.

BERNARD YELLIN.
